UNITED STATES PATENT OFFICE.

MONTGOMERY C. MEIGS, OF WASHINGTON, DISTRICT OF COLUMBIA.

REFLECTOR.

SPECIFICATION forming part of Letters Patent No. 281,600, dated August 24, 1880.

Application filed January 2, 1880.

To all whom it may concern:

Be it known that I, MONTGOMERY C. MEIGS, of Washington, in the District of Columbia, have invented certain new and useful Improvements in Reflectors, (Case A;) and I do hereby declare that the following is a full, clear, and exact description of the invention; which will enable others skilled in the art to which it appertains to make and use the same, reference being had to the accompanying drawings, and to the letters of reference marked thereon, which form a part of this specification.

This invention relates to an improvement in reflectors shown in Patents Nos. 209,178 and 209,576, granted to me, having for its object to so improve the construction of the same as to make them applicable to head-lights, street-car lamps, &c.; and it consists in the construction and arrangement of parts, as will be hereinafter more fully set forth, and pointed out by the claim.

In the annexed drawings, which fully illustrate my invention, Figure 1 is a front elevation, and Fig. 2 is a side elevation, of my improved reflector.

A represents the reflector, which may be of ellipsoidal, paraboloidal, or hyperboloidal form. In the bottom of said reflector is formed an opening, *a*, of the form shown, adapted to receive the chimney of a lamp, B. The rear part of the reflector is open, and is provided with the lips *b*, curved in the line of the shape of the re-

flector, which act as fingers to embrace the chimney and support the reflector thereon, as shown.

By this arrangement a head-light can be easily and cheaply constructed.

The utility of the device is obvious as applied to the street-car lamp. The opening *a* admits the light through it for the purpose of lighting the car, and at the same time the light is reflected and thrown forward with great brilliancy along the track.

Different-colored glasses may be placed at the mouth of the reflector, if desired, thus making the device act as a signal-light, thus cheapening the cost of the lamps for street-cars, and rendering them perfectly simple and at the same time not liable to get out of repair.

Having thus fully described my invention, what I claim as new, and desire to secure by Letters Patent, is—

In a head-light or street-car lamp, the reflector A, open at its rear and provided with the curved lips *b*, said lips adapted to act as fingers and embrace a chimney, substantially as shown, and for the purpose set forth.

In testimony that I claim the foregoing as my own I have hereto affixed my signature in presence of two witnesses.

MONTGOMERY C. MEIGS.
